UNITED STATES PATENT OFFICE.

WILHELM RODENHAUSER, OF VÖLKLINGEN, GERMANY, ASSIGNOR TO THE GRÖNDAL KJELLIN COMPANY, LIMITED, OF LONDON, ENGLAND.

FURNACE FOR METALLURGICAL PURPOSES.

984,970.

Specification of Letters Patent. Patented Feb. 21, 1911.

Application filed November 3, 1908. Serial No. 460,956.

To all whom it may concern:

Be it known that I, WILHELM RODENHAUSER, a subject of the Emperor of Germany, residing at 58 Poststrasse, Völklingen an der Saar, in the Empire of Germany, have invented certain new and useful Improvements in and Relating to Furnaces for Metallurgical Purposes, of which the following is a specification.

10 This invention relates to furnaces for metallurgical purposes, the chief object being to provide an improved furnace in which the material to be treated can be more uniformly heated than in furnaces of the kind 15 now in use.

Metallurgical furnaces hitherto employed are defective owing to the uneven distribution of the heat that is imparted to the material to be melted. In electric arc furnaces, 20 for example, the charge in the melting chamber is very irregularly heated, because the electric current in passing from one electrode to the other creates an electric arc which acts directly upon a portion of the 25 furnace of the charge only, the remainder of the charge being only heated indirectly by conduction from the portion that is directly exposed to the source of heat. This is true not only of the electric arc furnace in the 30 narrow sense, that is to say of a furnace in which an electric arc passes between the oppositely placed extremities of two electrodes presenting the form of rods and located above the material to be melted, but also applies to electric furnaces of the kind in which 35 an electric current passes into the charge by way of a rod electrode, then crosses, in the form of an arc, a narrow air gap between the electrode and a layer of slag, 40 and after passing through the slag, or slag and metal, leaves the furnace by way of another air gap and electrode (Heroult furnace), or by way of a plate inserted in the bottom of the furnace. Even in this latter 45 form of furnace, the current that, after passing the air gap, flows through the material under treatment, is, quite apart from the fact that it flows through it with comparatively low density only, far too low to produce any considerable quantity of heat in 50 it owing to its good electric conductivity. Practically speaking in this furnace also, heat is produced exclusively near the electric arc so that substantially only the surface 55 of the material is directly heated.

When it is further considered that the more or less coarse material stacked in the furnace at the beginning of the melting operation constitutes a bad conductor of heat, it will be readily understood that the melting of the portions of the material located near to the electric arc or to the electrodes will take place much sooner than the melting of those parts which are located at a greater distance; a considerable period of 60 time will therefore elapse before the whole of the material has become sufficiently fluid, and during this time much heat is lost by radiation and conduction. For this reason the thermic efficiency of these furnaces 65 must be low. The vigorous heating of the material almost exclusively at the surface as above referred to presents the further defect that the material is not thoroughly mixed. The top layer of the material upon 70 which the electric arc directly acts is always much hotter and therefore specifically lighter than the lower layers which, practically speaking, are only heated by conduction. A circulatory movement of the material cannot therefore be expected even after the melting has been completely effected. The material withdrawn from the furnace must therefore be mixed and rendered homogeneous by a special operation, 75 or the furnace must be adapted to be tilted so that the material may be displaced by rocking the furnace while the melting operation is in progress. Both of these methods of mixing the molten material and rendering it homogeneous are of course inconvenient and expensive in practice.

The same defects, which as described above are inherent in the electric arc furnaces heretofore used, also occur in flame or reverberatory furnaces such as Martin furnaces, in which the heating of the material is effected by the action of furnace gases passing over it; for it will be readily understood that in this case also only the upper parts of 80 the material are directly heated. Moreover owing to the irregular heating of the various parts of the material much time and utilizable heat are lost, and for the reasons already stated no circulatory movement of 85 the material takes place. A consideration of these defects has led to the present invention which resides in the fact that metallurgical furnaces of the kind above referred to are provided, in addition to the arc, 90

flame or other source of heat acting upon the surface of the charge, with a second or auxiliary source of heat of an electrical nature which renders it possible to positively 5 heat the lower part of the charge, and thereby effect a circulatory movement of the same and a more uniform distribution of heat than in the prior arrangements above referred to.

10 In order that the said invention may be clearly understood and readily carried into effect, I will proceed to describe the same more fully with reference to the accompanying drawings which show several types of 15 furnaces to which my invention is applied.

Figure 1 is a vertical section, and Fig. 2 a sectional plan on the line 2—2 of Fig. 1 showing my invention applied to an electric-arc furnace. Fig. 3 is a sectional plan 20 of a modified form of furnace, rectangular in plan. Fig. 4 is a vertical section and Fig. 5 a horizontal section on the line 5—5 of Fig. 4 illustrating a furnace with two electrodes suspended vertically above the 25 charge in the melting chamber, a small air gap being provided between the end face of each of the electrodes and the surface of the charge, so that two arcs in series are formed across the two air gaps when the electric 30 current passes. Fig. 6 is a vertical section, and Fig. 7 a horizontal section on the line 7—7 of Fig. 6 illustrating a modified form of the furnace shown in Figs. 4 and 5, in which only one electrode is placed above the 35 charge in the melting chamber, the other electrode, which may be a water cooled steel plate, being built or let into the bottom of the chamber.

In each of these figures, A A represent 40 the terminal plates of the electrodes by means of which the second source of heat is introduced into the furnace in accordance with this invention.

B represents the furnace walls, and C the 45 refractory lining.

E' and E² are the electrodes between which the electric arc is struck.

The electrodes, by which the second source 50 of heat is introduced, are built inside the furnace wall B below the surface of the charge and directly in contact therewith at suitable places. These electrodes may consist of two main parts; one part b is a plate-like layer of refractory material which is a 55 conductor of electricity at high temperatures only, but which for the purpose of rendering it a sufficiently good conductor even in a cold state is mixed with a carbonaceous binding medium, say tar or powdered carbon; the other part a is a metal plate equal 60 in superficial area to the plate-like layer of refractory material b and embedded between this material and the furnace wall B. The electrode terminals A, A are attached to 65 or form part of these metal plates a; on the

side that is in contact with the refractory layer, each plate may be formed with recesses or channels of dovetail or similar cross-section, with the object of preventing the layer of refractory material from becoming detached from the metal plate and also of increasing the area for the transmission of the current. The current serving to feed these electrodes may be taken, in the case of electric arc furnaces, from the same 75 source of current as that which serves to feed the arc. If a transformer is used, the arrangement may be such that its secondary winding is subdivided so that only a part of the winding, which may consist of thick 80 wire or bars, serves to supply the current for feeding the electrodes which are let into the furnace wall at the lower part of the furnace. The remaining windings which may consist of fine wires or rods, and the sec- 85 ondary windings as a whole, serve for the generation of a current of appropriate voltage for feeding the electric arc.

In the case of flame or reverberatory furnaces, such as Martin furnaces, the above 90 described method of heating the lower parts of the metal bath by heat derived from electrical resistance may be employed at any time to assist in the heating of the charge by the hot gases without incurring injury to 95 the electrodes by the action of the hot gases upon them. It may be found advantageous to apply this method of heating to converters for the manufacture of steel, thereby enabling the temperature of the molten mass 100 in the converter to be increased during the blowing operations or the bath to be heated and thereby drive out any objectionable gases that may be formed.

In all constructions the electrode plates are 105 arranged inside the furnace walls in such a manner that the current conducted to the plates is obliged to flow through the lower part of the material that is being melted. By suitably regulating this current, the heating 110 of the material can be rendered thoroughgoingly uniform.

What I claim and desire to secure by Letters Patent of the United States is:—

1. A furnace for melting metal, comprising a melting chamber in which the charge is contained, electric means for heating the surface of the charge and independent electric means below the surface of the charge for leading an electric current to the body 115 of the latter whereby a substantially uniform heat may be maintained in all portions thereof, substantially as described.

2. A furnace for melting metals, comprising a melting chamber in which the charge is contained, means for heating the surface of the charge, and electric conductors forming portion of the lining of the melting chamber below the surface of the charge for leading an electric current to the body of the latter, 125 130

whereby a substantially uniform heat may be maintained in all portions thereof, substantially as described.

3. A furnace for melting metals, comprising a melting chamber in which the charge is contained, electric arcing means for heating the surface of the charge and electric conductors forming portion of the wall of the chamber below the surface of the charge, 10 for leading a current to the body of the latter, whereby a substantially uniform heat may be maintained in all portions thereof, substantially as described.

4. A furnace for melting metals, comprising a melting chamber in which the charge

is maintained, means for heating the surface of the charge, in combination with electric conductors forming portion of the wall of the chamber below the surface of the charge for leading a current to the body of the 20 latter whereby a substantially uniform heat may be maintained in all portions thereof, substantially as described.

In testimony whereof I affix my signature in presence of two witnesses.

WILHELM RODENHAUSER.
